UNITED STATES PATENT OFFICE.

JOHN J. O'MARA, OF NEW YORK, N. Y.

CASSEROLE-FRAME.

1,118,794.

Specification of Letters Patent. Patented Nov. 24, 1914.

Application filed March 11, 1914. Serial No. 824,032.

To all whom it may concern:

Be it known that I, JOHN J. O'MARA, a citizen of the United States, and a resident of the city of New York, borough of Brooklyn, in the county of Kings and State of New York, have invented a new and Improved Casserole-Frame, of which the following is a full, clear, and exact description.

This invention relates to improvements in 10 casserole frames or similar utensils and more particularly to an improved article of the above character employing an improved method of joining the ends of a band of solid or reticulated material and simultaneously forming a foot and handle and rendering the band continuous in appearance.

With the above and other objects in view, the invention resides in the peculiar combination and arrangement of parts to be 20 hereinafter more fully described, illustrated and claimed, it being also an object to provide a device which is simple in construction, durable and efficient.

Reference is to be had to the accompanying drawings forming a part of this specification, in which similar characters of reference indicate corresponding parts in all the views and in which—

Figure 1 is a fragmentary elevation 30 partly in section showing the band of a casserole frame with its ends joined in accordance with my improvement; Fig. 2 is a face view of the structure shown in Fig. 1; and Fig. 3 is a horizontal sectional view 35 taken on the line 3—3 of Fig. 1.

In carrying out my invention I am aware that it is old to produce a combined handle and foot for utensils, also to join the two ends of a band by some connecting means 40 and also to anchor a combined handle and foot or a handle alone by means engaging the body or band, but I am not aware of any improvement in which a combined handle and foot are simultaneously made, cast or 45 molded, while at the same time anchoring or connecting the ends of a suitable length of metal to form a continuous band and at the same time covering the seam. By this means not only is the formation of the joint 50 facilitated and the foot and handle formed at the same time, but the seams are covered and are rendered invisible on the inside and outside and all are cast or molded in one piece in such a manner as to appear as a 55 part of the band itself and to be thoroughly strong and reliable.

By way of illustration a fragmentary portion 10 of a casserole frame or cooking utensil is shown, it being understood that the material from which it is formed can be 60 of any suitable design. I prefer, however, to roll the upper and lower edges of the band or strip from which the latter is constructed, as shown at 11, the rolls containing reinforcing or stay wires 12 so as to 65 form beads at the top and bottom edges and to strengthen the structure as well as to cause it to retain its shape. The wires 12 may be suitably embedded in the metal in any other manner than that described without departing from the spirit of the invention. 70

When the ends of the band are to be connected they are brought into contact as shown at 13 in Fig. 3 of the drawings and 75 if the band is not already provided with openings such openings are provided adjacent the ends of the connected parts, as shown at 14, and a suitable mold having been provided, depending upon the particular design of the handle and foot, a handle 15 is molded with an integral foot 16 to provide a connecting part 17 between the top and bottom portions of the handle. The connecting portion of the metal forming the 80 same will pass through the openings 14, which may be of suitable number and size, and will pass inside of the band to form an inside reinforcing part 18 extending up as far as the top bead 11. At the bottom an 85 inwardly projecting lug 19 will be formed to produce a shoulder adapted to coöperate with any other number of shoulders provided inside of the band at the lower part, so as to support a dish or cooking utensil in 90 the frame.

The particular design or shape of the handle and foot and connecting part for the extremities of the band may be varied at will without departing from the spirit of 100 the invention, but it is here stated that the improved method of joining the ends of the band is especially adapted for casserole frames or supports for cooking utensils when constructed of malleable metal, but 105 may be adapted to the cooking utensils themselves. Therefore it will be seen that the invention specifically resides in the method or device for providing a combined handle and foot and at the same time connecting the ends of the band and covering 110 the seams both on the inside and outside,

and especially in which all of the said parts are cast or molded from one piece so that the joint is not visible and is molded into the connection.

5 Having thus described my invention, what I claim as new and desire to secure by Letters Patent is:—

1. A casserole frame, comprising a band having perforations near its extremities, 10 and a handle, foot and connecting part molded on to the band to extend through the perforations and cover the co-acting ends of the band.

2. An improved casserole frame which 15 consists of a strip with perforations and a handle cast to the frame to produce inner and outer connecting portions for the seam at the contacting ends of the strip, the material passing through the perforations to 20 join the connecting portions and anchor the handle.

3. A casserole frame comprising a continuous strip with its ends in contact and perforations therethrough adjacent to said 25 ends, and a handle having top and bottom portions cast integral and simultaneously with a connection between said top and bottom portions and along the inner and outer faces of the seam produced by said contacting ends with the material passing through the perforations to join said ends.

4. A casserole frame comprising a strip with its ends in contact and perforated adjacent thereto, and a foot cast on the frame

with inner and outer connecting portions at 35 the meeting ends of the strip and passing through the perforations.

5. A casserole frame comprising a strip with its ends in contact and perforated adjacent thereto, a foot cast on the frame with 40 inner and outer connecting portions at the meeting ends of the strip and passing through the perforations, and an inwardly projected bead simultaneously formed with the foot and inner connecting portion at the 45 bottom edge of the strip.

6. An improved article of manufacture, comprising a utensil consisting of a strip bent to form a continuous band open at its top and bottom and having beads at its top 50 and bottom edges, the ends of the strip being brought together edge to edge and having perforations therethrough, and a handle comprising a grasping part cast to the band with inner and outer connecting 55 portions covering the seam produced, the material passing through the perforations to join the connecting portions and having a foot and inwardly projecting lug formed integral therewith.

In testimony whereof I have signed my name to this specification in the presence of two subscribing witnesses.

JOHN J. O'MARA.
